(57) **CLAIM**

The ornamental design for a pizza cutter, as shown and described.

DESCRIPTION

FIG. 1 is a front perspective view of a pizza cutter, showing my new design;

FIG. 2 is a rear perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is a front perspective view of the pizza cutter with its cover, indicating the usage environment of pizza cutter with its cover.

The dashed broken lines in the figures are for the purposes of illustrating portions of the pizza cutter that form no part of the claimed design.

The dashed broken lines in the FIG. 9 are for the purposes of indicating the usage environment of the pizza cutter and form no part of the claimed design.
